(57) **CLAIM**

The ornamental design for a heating external application material, as shown and described.

DESCRIPTION

FIG. 1 is a front view of the heating external application material showing our new design;
FIG. 2 is a top plane view thereof;
FIG. 3 is a right side view thereof;
FIG. 4 is a left side view thereof;
FIG. 5 is a back view thereof; and,
FIG. 6 is a bottom view thereof.
